UNITED STATES PATENT OFFICE

107,617

DESIGN FOR A TEXTILE FABRIC

Edward P. Hullings, Mount Holly, N. J.

Application November 24, 1937, Serial No. 73,165

Term of patent 3½ years

To all whom it may concern:

Be it known that I, Edward P. Hullings, a citizen of the United States of America, residing in the city of Mount Holly, State of New Jersey, have invented a new, original, and ornamental Design for a Textile Fabric, of which the following is a specification, reference being had to the accompanying drawing, forming part thereof, wherein,

The figure is a plan view of a piece of textile fabric showing my new design.

I claim:

The ornamental design for a textile fabric, substantially as shown.

EDWARD P. HULLINGS.
